UNITED STATES PATENT OFFICE.

DAVID COLE, OF TUCSON, ARIZONA.

GRINDING-MILL.

1,222,184.

Specification of Letters Patent. Patented Apr. 10, 1917.

Application filed April 28, 1913. Serial No. 764,135.

To all whom it may concern:

Be it known that I, DAVID COLE, a citizen of the United States, residing at Tucson, in the county of Pima and State of Arizona, have invented certain new and useful Improvements in Grinding-Mills, of which the following is a specification.

This invention relates to grinding mills, particularly those intended for grinding ore.

10 The purpose of the invention is to construct an efficient ball or pebble mill which shall be shorter and more compact than those heretofore in use, and which shall discharge a substantially uniform finely ground product. The principle of the invention is the use with a relatively short grinding chamber of a sorting chamber of somewhat less diameter, and arranged to discharge the finely ground material from the mill and return 15 the coarse material to the grinding chamber. The use of the sorting chamber makes it unnecessary to use the relatively long grinding chamber heretofore considered essential to fine grinding in this class of mill, and consequently effects a saving in power.

The preferred embodiment of my invention is illustrated in the accompanying drawings, in which:—

Figure 1 is a vertical longitudinal section 20 of the complete mill;

Fig. 2 is an end view, partly sectional, of the same;

Fig. 3 is a section on the line 3-3 of Fig. 1; and

Fig. 4 is a perspective view of one of the lining sections used in the grinding chamber.

The mill is carried on foundation piers 1, provided with bearing boxes 2. In these are 25 mounted the self-aligning bearings 3.

The shell of the mill drum consists of five main castings bolted together. These are the hollow inlet trunnion 4 and the hollow outlet trunnion 5, each turning in a bearing 3, the two sections 6 and 7 which together comprise an oblate spheroidal grinding chamber connected to the inlet trunnion, and a cylinder section 8 which forms the sorting chamber between the above-mentioned grinding chamber and the outlet trunnion.

The inlet trunnion is provided with a funnel shaped liner 9 bolted in place so as to be renewed when worn out. Similarly a liner 10 having the radial vanes 11 at its inner

end, is provided for the outlet trunnion and is held in place by the lining of the sorting chamber. This lining consists of a main lining 12, made up of arc shaped silex blocks or other suitable hard material, with an intervening, spiral, inwardly projecting rib 13 60 preferably formed of manganese steel as are the liners 9 and 10. The parts numbered 10, 12 and 13 are confined by a lining ring 14 bolted in place as shown.

The grinding chamber is lined with two 65 complementary series of trough shaped curved manganese steel castings 15 of the form clearly shown in Fig. 4. These are readily removed for replacement by separating the shell sections 6 and 7. They are not bolted in position, but are self-sustaining. The liner castings 15 impart to the grinding chamber a ribbed inner surface, which tends to prevent slippage of the charge, and protects itself from wear by the accumulation of 70 rock and earth between the ribs.

A three armed Archimedes screw feeder 16 is attached to the inlet trunnion and carries the solid material mixed with the proper quantity of water into the mill. The mill is 75 driven by means of a large gear 17 bolted to flanges 18 on section 6 of the casing. The gear 17 is driven by a pinion 19 on shaft 20, which receives its power through belt 21.

The mill is rotated in such direction that the flanges 13 tend to convey back to the grinding chamber any material lying between them. When the mill is driven, solid material and water are fed into the grinding 80 chamber by the Archimedes screw 16. In this chamber the solids are gradually ground up by attrition of the particles fed to the mill as well as through the grinding action 85 of pebbles supplied to the mill for that purpose.

In order to secure an efficient grinding action in the grinding chamber it is essential to avoid slippage of the charge in the chamber, and such slippage is prevented, first by the ribbed lining, and second by the curved form of the chamber which conduces to a wedging action of the mass of the charge in the chamber.

The flow of water through the grinding 90 chamber picks up the finer particles and carries them into the sorting chamber and during the flow through the sorting chamber

ber a settling action takes place. The finest particles are carried out through the discharge trunion, while the coarser settle between ribs 13 in the sorting chamber and are then conveyed back to the grinding chamber. The radial ribs 11 by lifting and then discharging solid material down through the outflowing water, assist the sorting action.

10 The use of a sorting chamber of smaller diameter than the grinding chamber is of special advantage in that there is no tendency for the unground charge in the mill to flow into the sorting chamber. The only 15 solid material which enters the sorting chamber is that which has been ground fine enough to be sustained by the outflowing water current. The coarse portions of this are precipitated in the sorting chamber and thence 20 returned to the grinding chamber, but the finely ground portions are sustained by the water and overflow with it through the discharge opening.

The operation of my mill secures a marked 25 economy of power particularly in cases where fine grinding is necessary. For example a plain cylindrical mill for doing such grinding will commonly be twenty-two feet in length. Tests have shown that about 50% 30 of the reduction occurs in the first five feet and about 70% in the first ten feet, twelve feet being necessary to effect the final 30% of the reduction, the grinding action being less, due to the smallness of the particles. 35 The power consumed by a cylindrical mill is practically directly proportional to the length of the mill, so that obviously the efficiency of the mill can be greatly increased if the desired grinding can be effected in a 40 shorter mill in which the fine grinding takes place in the presence of the coarser particles.

I effect this purpose by adding to a relatively short grinding chamber, a sorting 45 chamber of suitable length, through which water flows to discharge and in which is effected a sorting action based on the laws of bodies settling in water. By this sorting action the particles which are sufficiently fine 50 to remain in suspension through the length of the sorting chamber are discharged while those which are precipitated are returned to the grinding chamber. Within certain limits the fineness of grinding can be varied by 55 the rate of feed of water to the mill and by varying the length of the grinding and sorting chambers. The product of the mill is characterized by uniformity of size.

Various forms of sorting chamber will 60 suggest themselves and also various forms of return conveying devices for the precipitated material, but I prefer those shown as the most simple. For example it is not necessary that the spiral rib 13 be continuous, or that it extend the full length of the chamber.

ber, so long as its form is such as to cause a tendency to move the precipitated material back toward the grinding chamber as it accumulates in quantity.

Having thus described my invention, what I claim is:—

1. In a grinding mill the combination of a rotatable grinding chamber; means for feeding water and material to be ground to the grinding chamber; a water conveying sorting chamber turning with the grinding chamber and in free axial communication therewith, said sorting chamber having a free axial overflow opening above the bottom of said chamber and at a point remote from the grinding chamber for producing an outflowing water current through the sorting chamber to carry ground material from the grinding chamber; and backwardly feeding conveying means in the sorting chamber for conveying back to the grinding chamber material precipitated from said outflowing water current. 75

2. In a grinding mill the combination of a rotatable grinding chamber; means for feeding water and material to be ground to the grinding chamber; a water conveying sorting chamber turning with the grinding chamber and in free axial communication therewith, said sorting chamber having a free axial overflow opening above the bottom of said chamber and at a point remote from the grinding chamber for producing an outflowing water current through the sorting chamber to carry ground material from the grinding chamber; and a backwardly feeding helical conveying rib on the walls of said sorting chamber for conveying back to the grinding chamber material precipitated from said outflowing water current. 90

3. In a grinding mill the combination of a member rotatable on a substantially horizontal axis and provided with a grinding chamber and a communicating water conveying sorting chamber of less diameter arranged in axial alignment, and further provided with an axial overflow discharge opening leading from said sorting chamber at a point remote from the grinding chamber and above the bottom of the sorting chamber; and means for feeding to said grinding chamber water and material to be ground. 100

4. In a grinding mill the combination of a rotatable member provided with a grinding chamber, a sorting chamber of less diameter than the grinding chamber and a free overflow discharge opening leading from the sorting chamber at a point remote from the grinding chamber said chambers being in free communication with each other and in substantially horizontal axial alignment; means for feeding water and material to be ground to said grinding chamber; and backwardly feeding conveying means mounted in said sorting chamber and 115

operable by the rotation of said rotatable member for conveying back to said grinding chamber solid material precipitated from said water in its flow through the sorting chamber to said discharge opening.

5. In a grinding mill the combination of a rotatable member provided with a grinding chamber, a sorting chamber of less diameter than the grinding chamber and a 10 free overflow discharge opening leading from the sorting chamber at a point remote from the grinding chamber, said chambers being in free communication with each other and in substantially horizontal axial alignment; means for feeding water and material to be ground to said grinding chamber; and a backwardly feeding helical conveyer member fixedly mounted in said sorting chamber to turn therewith, for conveying back 15 to said grinding chamber solid material precipitated from said water in its flow through the sorting chamber to said discharge opening.

6. In a grinding mill the combination of 20 a rotatable spheroidal grinding chamber; a cylindrical sorting chamber of less diameter, mounted to rotate coaxially therewith and adapted to effect a sorting action by free settling in water; an inclined inwardly projecting conveyer blade mounted 25 in the sorting chamber and adapted to exert a feeding tendency toward the grinding chamber upon material precipitated in the sorting chamber, the sorting chamber being 30 interposed between the grinding chamber and the discharge from the mill; and means 35

for feeding to the grinding chamber, water and material to be ground.

7. In a grinding mill the combination of a rotatable spheroidal grinding chamber; a cylindrical sorting chamber of less diameter, mounted to rotate coaxially therewith and adapted to effect a sorting action by free settling in water; a spiral inwardly projecting blade mounted in the sorting 40 chamber and adapted to exert a feeding tendency toward the grinding chamber, upon material precipitated in the sorting chamber, the sorting chamber being interposed between the grinding chamber and the discharge from the mill; a plurality of 45 radial vanes mounted in the sorting chamber adjacent the point of discharge from the mill; and means for feeding to the grinding chamber, water and material to be 50 ground.

8. A grinding chamber for mills comprising a globular shell formed in sections, and a lining therefor comprising a plurality of curved segmental lining bars provided with 55 marginal inwardly extending ribs, said bars being adapted to sustain themselves in position within said shell, by their arched arrangement.

In testimony whereof I have signed my 60 name to this specification in the presence of two subscribing witnesses.

DAVID COLE.
